GARMENT

Oscar A. Berman, Brooklyn, N. Y.

Refiled for abandoned application Serial No. 675,367, June 12, 1933. This application August 28, 1936, Serial No. 98,433

3 Claims.

(Cl. 2—74)

This application is a refiled application, the original application being Serial No. 675,367 filed June 12, 1933.

My invention relates to improvements in garments, and objects of my invention are first, to provide means by which a garment can easily be made comfortably and healthfully adjustable to the body of the wearer; second, to provide a garment that will fit persons of various sizes, types or builds and third to provide means by which a garment of this type can be made healthfully and comfortably self-adjusting to variations in body measurements, and automatically conformable to varying positions of the diaphragm, muscles and other parts of the body in standing, stooping, walking, bending, sitting, running, exercising, playing, working, etc., at the same time retaining its fit, style and sightliness without exposing the body or undergarments of the wearer.

To fully explain the advantages of my invention I shall refer briefly to the construction of well-known types of wrap-a-round garments. One of these, generally known as the Hoover apron, has belt portions which pass through vertical openings in the sides of the garment and join with a button in the back. These garments have not to my knowledge been provided with means for conforming to the body of the wearer, as claimed herein, nor for automatic adjustment to variations in the waist measurement of the wearer, as claimed herein, and the vertical openings tend to gap and expose the body or the undergarments of the wearer. Another garment of the wrap-a-round type is constructed similarly to the Hoover apron except that the belt portions instead of buttoning together at the back, tie together in a knot. The disadvantages of this type of garment are numerous. There is danger of the strings being caught in machinery, furniture or other objects.

Furthermore, if the strings are drawn tightly the body of the wearer is held under constant pressure, a condition not conducive to the comfort or health of the wearer. This pressure increases in varying positions of the body in motion. If the strings are not pulled tightly, the lapped-over portions sag, causing the garment to present an unsightly appearance. Besides the slipping of the strings through the vertical openings in the sides of the garment tends to cause them to twist, making it necessary for the wearer to give thought and time to straighten out the strings every time the garment is put on, and in this type of garment there is also a tendency for

the vertical openings to gap and expose the body or the undergarments of the wearer.

I attain the objects of my invention by mechanism illustrated in the accompanying drawing in which Fig. 1 is a front view showing the appearance of the garment just after it has been slipped on the wearer; Fig. 2 is a cross sectional view showing one side only of the garment lapped over and fixed in place; Fig. 3 is a cross sectional view showing both sides lapped into their final position and held by linked buttons; Fig. 4 is a front elevation showing construction of the linked buttons.

Similar numerals refer to similar parts throughout the several views. The bodice 10, 15 and skirt 11, and the belt between them constitute the basic garment. The belt itself comprises a main section, the elastic sections 13 and 16 and the tabs 12 and 17. The main section 21 contains a series of button holes 15, 20, 24, 20 and 25, and each of the tabs 12 and 17 contain button holes 14 and 18.

In donning the garment the wearer slips it over her shoulders, wraps the skirt 11 to the right side of the body as shown in Fig. 2 and passes button 19 through holes 14 and 15, then wraps the right side of skirt 23 to the left side of the body and passes button 19 through button holes 22 and 18. For closer adjustment button hole 24 or 25 is used instead of button hole 22. The elastic sections 13 and 16, automatically provide the variable adjustment for the fixed spaces between the button holes.

Having described my invention, what I claim as new and wish to protect by Letters Patent is:

1. In a garment of the wrap-a-round type, the combination of a bodice and a skirt with a belt of non-elastic material sewn in between the bodice and the skirt, the belt being extended at one of its outer edges by the addition of a piece 40 of elastic material, means for releasably securing the elastic material to one side of the garment and means for releasably securing the other end of the belt to the opposite side of the garment, thereby releasably retaining the lapped-over portions of the garment in corresponding positions.

2. In a garment of the wrap-a-round type, the combination of a bodice and a skirt with a belt of non-elastic material sewn in between the bodice and the skirt, the belt being extended at 50 its outer edges by the addition of pieces of elastic material, to the outer ends of which elastic material are fixed tabs of non-elastic material, in each of which tabs a button hole is set, the main portion of the belt also containing button holes,

together with means for holding the lapped-over portions of the garment in corresponding positions.

3. In a garment of the wrap-a-round type, the combination of a bodice and a skirt with a belt of non-elastic material sewn in between the bodice and the skirt, the belt being extended at the outer edges of the garment by the addition of strips of elastic material of the same width as the non-elastic belt, to the outer ends of which elastic material are sewn tabs of non-elastic material pointed at their farthest extremities, a

button hole worked in the pointed end of each of said tabs, the main portion of the belt containing a series of button holes on each side thereof, and linked buttons releasably securing either side of the front of the garment in a lapped over position on top of the other side, conforming the garment to the body of the wearer and automatically adjusting it to variations of the diaphragm, muscles and other parts of the body of the wearer.
